MULTIPLEX ANTENNA DISTRIBUTION
SYSTEM

Edward Lacey, Los Angeles, Calif.

Application December 8, 1948, Serial No. 64,063

19 Claims. (Cl. 343—205)

(Granted under the act of March 3, 1883, as
amended April 30, 1928; 370 O. G. 757)

1

This invention relates to multiplex circuits, and more specifically to multiplex receiving circuits wherein a plurality of communication channels may be maintained over a common transmission means, such as an antenna, the several channeled signals being separated at the receiving end by a plurality of tuned circuits, each resonant to the particular signal which it is desired that it extract from the antenna.

It is an object of this invention to provide an improved multiplex circuit in which each of the individual channels presents a relatively high impedance to the common transmission means, except when tuned to resonance, under which condition it presents an impedance matching that of the transmission means, whereby optimum energy transfer may be effected. Off resonance, the high impedance prevents an undesirable drain of energy from the common transmission means.

It is another object of this invention to provide a multiplex circuit in which each individual resonant circuit has a very high Q.

In the design of multiplex circuits, either for receiving or transmitting, it is desired to have optimum energy transfer, at resonance, between the transmission means, such as the antenna, and the individual resonant circuit. This is achieved by matching the impedance of each individual circuit at resonance to the impedance of the antenna. It is also desirable that the impedance presented to the transmission means by each circuit when tuned off the resonant frequency, be quite high, in order that the particular circuit not drain energy from the antenna except when tuned to its own particular frequency. Briefly, it is desirable that a plot of impedance vs. frequency for each of the several multiplex circuits look somewhat like a V, the impedance above and below resonance being quite high, and dipping at resonance to the impedance value which is the conjugate of the impedance of the transmission means and the circuit, at which point the transfer of energy will be maximum, by virtue of the impedance match.

It is also desirable in multiplex circuits, in fact in many tuned circuits, that the energy loss in the circuit be kept to a minimum; that is to say, the circuit should have a high Q, or a high ratio: wL/R .

Prior art multiplex circuits have achieved each of these desiderata, but always at the expense of the other.

It is an object of the instant invention to achieve both these desirable features simultaneously in a multiplex system.

2

It is another object to minimize cross-coupling between the several multiplexed circuits of the system.

It is a further object of the instant invention to provide a multiplex system which is broad-band in its overall characteristics; wherein each individual circuit will present, at resonance, an optimum impedance match to the common transmission means to which each circuit is coupled; and wherein each individual circuit will have a high Q.

It is a still further object to attain the above outlined desiderata without the use of vacuum tubes with their consequent vulnerability to overloading.

Other objects and many of the attendant advantages of this invention will be readily appreciated as the same becomes better understood by reference to the following description.

20 The multiplex circuit of the instant invention comprises a transmission means to which each of the several multiplex circuits is coupled in some suitable fashion. For purposes of example and to simplify the disclosure, the multiplex circuit will be shown as a receiving circuit, although it is to be understood that the teachings of the instant invention are equally applicable to a transmitting circuit. Furthermore, the transmission means common to the several individual circuits will be shown as a fixed impedance, broad-band antenna, although it is to be understood that the teachings of the instant invention are equally applicable to other types of transmission means, such as a cable extending between a transmitting and receiving station of a multiplex transmission system.

In accordance with the instant invention, broad-band transformer means are coupled to the broad-band antenna. By the term "broad-band antenna" or "broad-band transformer means" is meant a means in which the impedance, or impedance ratio, respectively, is substantially constant over a wide frequency range, so that within that range the reaction of the particular means is the same to all frequencies.

40 The essence of the instant invention is the combination, with the transformer means described above, of a plurality of series-resonant circuits connected to the other side of the transformer means. As a general rule, the impedance of the antenna and of the transmission line to which it is connected is not very low, being in the order of perhaps 50 ohms, which figure will be used hereinafter as exemplary of the transmission means impedance. The impedance of a series-resonant circuit, properly constructed, is

at resonance quite low, being in the order of 1 ohm, which figure will be employed herein-after as exemplary of the impedance of each series-resonant circuit at resonance. The essence of the instant invention, therefore, is the use of step-down, broad-band transformer means coupling the 50 ohm impedance of the antenna to the 1 ohm resonant impedance of each series-resonant circuit. The high turns terminals, that is, the terminals on the 50 ohm side of the transformer, are connected to the antenna. The several multiplexed series-resonant circuits are connected to the low turns terminals of the transformer means, that is, the terminals on the low impedance side of the transformer. For the exemplary figures given above, the transformer means would be one having an impedance ratio of 50 to 1 (a turns ratio of about 7 to 1).

Each of the generally similar multiplexed channels, which are fed with energy from the common antenna, includes, in addition to its series-resonant circuit (which is preferably made tunable), a signal amplifying means associated with or connected to a portion, i. e. one of the elements, of the series-resonant circuit. In the case of a receiving system, the amplifying means consists of suitable means for deriving a signal from the series-resonant circuit, and applying it to a suitable receiver. In the case of a transmitting system, the amplifying means consists of a suitable means for applying a signal of predetermined frequency to the series-resonant circuit, which would, in turn, apply it to the antenna through the transformer means above discussed.

The impedance of each of the several series-resonant circuits, at resonance, after reflection through the transformer means, is substantially matched to the impedance of the antenna. For the exemplary figures used above, the impedance of the series-resonant circuit, connected to the low turns side of the transmission means, being 1 ohm, is, after reflection thru the transformer, approximately 50 ohms, this being the impedance of the antenna itself. Thus at resonance, optimum impedance match is obtained between the antenna and the particular channel to which the incoming energy is fed. In well-designed circuits, the impedance of the antenna is substantially resistive, and of course, the impedance of a series-resonant circuit at resonance is also substantially resistive, so that it will be understood that matching of impedances referred to herein neglects reactive components, because in general they are not to be found in circuits of the present sort. It is to be understood, however, that where the antenna, or (more generally) the transmission means, includes a reactive component, it may still be matched to each circuit of the multiplex system by simply including the complement of the antenna reactance in the individual circuit, in accordance with known impedance matching teachings.

There will be described as examples of the instant invention, two major species, each of these species having certain minor modifications which might be desired for some applications. These embodiments of the instant invention will now be described in connection with the accompanying drawing, wherein:

Fig. 1 illustrates the first species of the instant invention, and is characterized by the use of a plurality of individual step-down transformers, as the broad-band transformer means, which is one of the essential features of the instant invention;

Fig. 1A illustrates certain minor modifications that are suitable for the circuit of Fig. 1 for particular applications;

Fig. 2 illustrates the second principal species of the instant invention, wherein the broad-band transformer means constitutes a single, step-down transformer, to the low turns side of which is connected a low impedance transmission line which feeds the several tunable series-resonant circuits included in the several multiplex channels of the complete system;

Fig. 2A illustrates how the circuit of Fig. 2 may be modified slightly for particular applications; and

Figs. 3 and 4 are included to illustrate the disadvantages of attempting to achieve a satisfactory multiplex system without the use of the broad-band, step-down transformer means constituting one of the essential features of the instant invention.

Referring to Fig. 1, a transmission means 11 is shown, to which is connected transformer means 12, feeding a plurality of generally similar multiplex channels 13, 14, and 16. For exemplary purposes, the transmission means has been shown as an antenna 17, which in the instant embodiment is broad-band and of fixed impedance, connected to a transmission line 18. For exemplary purposes, it will be assumed that the fixed impedance of the antenna 17 and of the transmission line 18 is 50 ohms.

In the species of Fig. 1, the transformer means 12 assumes the form of a plurality (in this case, three), of step-down, broad-band, powdered-iron core, transformers 19, 21, and 22, each having a turns ratio of $\sqrt{50}$ to 1. The high turns terminals of the transformer means 12 are connected, as shown, to the transmission line 18.

The multiplex channel 13, which is typical of the channels 13, 14, and 16, consists of a series-resonant circuit 23, connected to the low turns, or 1 ohm, terminals of the transformer 19. The series-resonant circuit 23 comprises an inductor 24, connected in series with a capacitor 26, the two in turn being connected to the secondary, or low turns, winding 27 of the transformer 19. The series-resonant circuit 23 makes no substantial use of the transformer 19 for tuning; the transformer serves only as an impedance matcher.

In the example of Fig. 1, a receiving circuit is shown. Therefore, radio frequency energy appearing across the capacitor 26 is applied between grid and cathode of a tube 28, which represents the first stage of a suitable receiver amplifier. The capacitor 26 is shown as variable, or adjustable, so that the channel 13 may be tuned to any desired frequency of the band which the receiving system of Fig. 1 is adapted to receive. The channels 14 and 16 are generally similar to the channel 13 described above.

The operation of the circuit of Fig. 1 will now be briefly considered.

Assume that the antenna 17 is receiving energy of three different frequencies, F1, F2, and F3. Channel 13, i. e. the series-resonant circuit 23, is tuned to F1; channel 14 is tuned to F2; and channel 16 is tuned to F3. The impedance of the series-resonant circuit 23, at the resonant frequency F1, will be very low, approximately 1 ohm.

Reflected through the transformer means 12, i. e. its transformer 19, this 1 ohm impedance appears on the transmission line 18 and antenna 17 as a 50 ohm impedance, exactly matching that of the antenna 17 and line 18. Therefore, for energy of frequency F1 there is optimum coupling and

maximum transfer of energy from the antenna 17 to the channel 13.

To all frequencies other than F_1 , channel 13, after reflection through the transformer means 12, presents a very high impedance, so that little energy is diverted into the channel 13, except at frequency F_1 . The degree to which frequencies other than F_1 are rejected by channel 13 is dependent directly on the character of the frequency response curve of the series-resonant circuit 23, which, in turn, depends directly upon the Q of the circuit. Assuming, purely for example, that the inductor 24 has an inductance of about 32 microhenries and that F_1 is 1 megacycle, the Q of the series-resonant circuit 23 is equal to:

$$wL/R = \frac{2 \times 3.14 \times 10^6 \times 32 \times 10^{-6}}{2} = \frac{200}{2} = 100$$

The term in the numerator is "wL;" the term in the denominator is the total resistance of the circuit, which is the 1 ohm impedance at resonance (pure resistance) of the series-resonant circuit 23, plus the 1 ohm impedance of the low turns winding 27 of the step-down transformer 19: a total of 2 ohms. Carrying forth the above calculations yields a value of 100 for the Q of the resonant circuit feeding the amplifying tube 28. This is a relatively high value, and results in excellent discrimination by the channel 13 against all frequencies except F_1 , to which it presents, as outlined above, the 50 ohms required to obtain maximum energy transfer from the antenna 17.

The channels 14 and 16 react to the frequencies F_2 and F_3 respectively, in a similar manner. It is, therefore, seen that the single antenna 17 is able to feed a large number of individual channels, each tuned to its own frequency, with each channel having little or no effect on reception by the other channels and taking energy from the antenna only at its own tuned frequency.

It has been found as a practical matter that it is often desirable to employ, as the transformer means 12, suitable auto-transformer means in place of the regular transformer exemplified at 19 in Fig. 1. In this event, the circuit of Fig. 1 may be modified as shown in Fig. 1A, wherein the auto-transformer 19' is connected with its high turns terminals to the antenna 17', the tapped low turns terminals being connected, as shown, to the series-resonant circuit 23', the variable capacitor 26' of which is connected in the usual manner across the grid-cathode of the amplifying tube 28'.

While theoretically the transformer 19, or 19', as the case may be, reflects 50 ohms into the primary for every ohm in the secondary, there is as a practical matter a tiny amount of flux leakage which results in a small inductive reactance in the transformer. This may be corrected as shown in Fig. 1A by the insertion of a small adjustable capacitor 31, in series with the high turns windings of the transformer 19'. It is to be understood that if desired this reactance-correcting capacitor may also be used with the regular transformer illustrated at 19 in Fig. 1.

A second principal species of the instant invention is illustrated in Fig. 2, wherein 17a represents the broad-band antenna having a fixed impedance of 50 ohms, for example. In this species, the step-down transformer means assumes the form of a single, powdered-iron core, radio frequency transformer 33, having a $\sqrt{50}$ to 1 turns ratio. The high turns, or 50 ohms, side of the transformer 33 is connected between ground and the antenna 17a. To the low turns winding

34 of the transformer 33 is connected a 1 ohm transmission line 36, to which are connected the several multiplexed channels 13a, 14a, and 16a.

Exemplary of the channels is the channel 13a, which comprises a series-resonant circuit 23a, consisting of the inductor 24a and the capacitor 26a, connected in series across the 1 ohm transmission line 36.

Operation of the Fig. 2 species of the instant invention, as a receiving circuit, will now be briefly considered. Assume that three frequencies, F_1 , F_2 , and F_3 are being received by the antenna 17a. By means of the adjustable or variable capacitor 26a the channel 13a is tuned to F_1 . Thus, at frequency F_1 , a 1 ohm impedance is applied across the 1 ohm transmission line 36, and to the low turns winding 34 of the transformer 33. This 1 ohm impedance is reflected through the transformer 33 at a 50 to 1 ratio, and appears on the high turns winding of the transformer 33 as a 50 ohm impedance. This impedance matches that of the antenna 17a, and of the associated transmission line 37, so that at F_1 there is optimum transfer of energy from the antenna 17a to the channel 13a. Frequencies other than F_1 are rejected by the series-resonant circuit 23a, because at all other frequencies its impedance is much higher than 1 ohm. Therefore, little or no energy other than that of F_1 will be drawn into the channel 13a. As in the first species, described in Fig. 1, the effectiveness of unwanted frequency rejection depends upon the Q of the circuit, which includes the capacitor 26a, the inductor 24a, and the low turns winding 34.

The latter having an impedance of approximately 1 ohm, reflected from the 50 ohm antenna 17a through the transformer 33, and the resonant circuit 23a having an impedance of 1 ohm, the total impedance (which is essentially resistive) is 2 ohms. As in the first example, the wL of the circuit is approximately 200, so that the Q of the circuit is in the order of 100, which is a very high Q, and which results in a sharp resonance curve and attendant excellent rejection of all frequencies except F_1 .

In a similar manner, the channels 14a and 16a reject all frequencies except F_2 and F_3 , respectively, to which they are responsive, respectively, with an impedance of 1 ohm, reflected through the transformer means 12a as a 50 ohm impedance, matching that of the antenna 17a.

It will be readily apparent that the transformer means 12 of Fig. 1 and the transformer means 12a of Fig. 2 are substantially equivalent, the former case using a 50 ohm line 18 to feed a plurality of 50 to 1 impedance ratio transformers, the latter using a 50 to 1 transformer 33 to feed a 1 ohm line 36, which in turn feeds the several channels of the system.

The circuit of Fig. 2 has the practical advantage of requiring only a single, powdered-iron core, broad-band, radio frequency transformer 33, instead of the plurality of transformers 19, 21, and 22 in the Fig. 1 circuit. It has the disadvantage, however, of requiring a 1 ohm transmission line 36 which, as a practical matter, is somewhat difficult of construction. In operation, however, the two circuits are obviously the full equivalent of each other.

Like Fig. 1, Fig. 2 also has its variant, shown in Fig. 2A, wherein the transformer 33 is replaced by the auto transformer 33', the other elements of the circuit remaining essentially unchanged. Likewise, as in Fig. 1A, the leakage reactance of the transformer (either 33 or 33') may be com-

pensated for by the insertion of a small variable capacitor 31a in series with the antenna and transformer primary which neutralizes any small inductive component in the transformer.

In order to emphasize the advantages of the instant invention, there will now be hypothesized two different circuits which do not meet the requirements of the instant invention, namely, step-down transformer means, coupling to a plurality of channels including tunable series-resonant circuits.

Consider first the hypothetical circuit of Fig. 3, which includes an antenna 41, connected to a transmission line 42, to which are directly connected a plurality of multiplexed channels 43, 44, etc. The channel 43, as an example, includes a series-resonant circuit 46, constituted of an inductor 47 and a variable capacitor 48, connected in series across the line 42. Since the resonance impedance of the circuit 46 is in the order of 1 ohm, it is necessary to connect in series with this circuit a resistive impedance 51 of about 49 ohms value, so that the impedance of the antenna 41, which is 50 ohms, may be substantially matched.

Consider, however, the effect of such an expedient upon the Q of the circuit. wL , as shown hereinbefore, is approximately 200. The resistance of the circuit, however, is now 1 ohm (circuit 46) plus 49 ohms (the resistor 51) plus 50 ohms (the antenna 41), a total of 100 ohms giving a net Q of approximately 2. This results in high energy loss and in lack of resolution, or unsharp tuning, for the channel 43. It is, therefore, evident that the hypothesized circuit of Fig. 3 lacks the high Q marking applicant's invention.

Next, hypothesize the circuit of Fig. 4, wherein an antenna 52 is connected to a 50 ohm transmission line 53, across which are coupled the multiplex channels 54, 56, etc. The channel 54, for example, includes a parallel resonant circuit 57, comprised of a variable capacitor 58 connected in parallel with an inductor 59. Energy is coupled to the inductor 59 by a coil 61 connected across the transmission line 53. While the coupling between the coils 61 and 59 constitutes a transformer in a sense, there is very great flux leakage between these coils, because the coil 59 must present a relatively high inductive reactance in order to resonate with the capacitor 58. Unlike the instant invention, the circuit 57 makes full use of the winding 59 to form the inductive component of the circuit.

The impedance reflected by the resonant circuit 57 into the transmission line 53 is highest at the tuned resonance point rather than lowest, as it should be, this being characteristic of all parallel resonance circuits. That is to say, off resonance, the impedance reflected into the line 53 by the circuit 57 is relatively low, and hence considerable energy will be drained from the line 53 without doing any good in the channel 54. At resonance, when the channel 54 is tuned to accept the energy, the impedance reflected into the line 53 will be maximum.

It is, therefore, evident that the hypothesized circuit of Fig. 4 has this disadvantage: the un-tuned channels tend to draw more energy from the line than does the channel which is tuned to the particular frequency of the energy. Thus, much energy is wasted, and the system is relatively low in efficiency.

From the above explanation, it will be seen that there has been disclosed herein (embodied in several species) a multiplexed circuit having simultaneously in combination the following ad-

vantages: it is broad-band within the frequency spectrum to which it may be tuned. Each particular channel has a very high Q, so that the energy loss is minimized. Each channel, when tuned to a particular frequency of incoming energy, has a perfect impedance match with the antenna or other transmission means feeding the system, so that optimum transfer of energy at the frequency is achieved. Because the coupling impedance (the 1 ohm secondaries) between any two circuits is so low compared to the untuned impedance of each circuit itself, the feedback or cross-coupling between circuits is reduced to a minimum. In this way the local oscillators of the respective receiving circuits do not cross feed appreciably into the other circuits, thru the transmission line. All of the above features are attained without the use of vacuum tubes, with their consequent danger of overloading due to near-by transmitters.

As stated hereinbefore, although the particular examples have illustrated receiving circuits employing fixed impedance antennas, it is obvious that, if desired, the teachings of the instant invention may be employed equally well for transmitting circuits. Likewise, the antennas illustrated herein may be replaced by any suitable transmission lines such as coaxial cables extending between receiving and transmitting stations. Obviously, many modifications and variations of the present invention are possible in the light of the above teachings. It is, therefore, to be understood that within the scope of the appended claims the invention may be practiced otherwise than as specifically described.

The invention described herein may be manufactured and used by or for the Government of the United States of America for governmental purposes without the payment of any royalties thereon or therefor.

What is claimed is:

1. A multiplex receiving circuit comprising a fixed impedance, broad-band antenna and a plurality of generally similar, multiplexed channels connected in parallel to said antenna, each channel including a broad-band, step-down transformer having its high turns terminals connected to said antenna, a tunable, series-resonant circuit connected across the low turns terminals of said transformer, the impedance of said circuit at resonance reflected thru its transformer being substantially matched to said fixed impedance of said antenna and being much higher off resonance; and a means for deriving a signal from one of the elements of said circuit.

2. A multiplex receiving circuit comprising broad-band transmission means; and a plurality of generally similar, multiplexed channels connected to said transmission means, each channel including a broad-band, step-down transformer having its high turns terminals connected to said transmission means, a tunable, series-resonant circuit connected across the low turns terminals of said transformer, the impedance of said circuit at resonance reflected thru its transformer being substantially matched to the impedance of said transmission means and being much higher off resonance, and a means for deriving a signal from one of the elements of said circuit.

3. A multiplex circuit comprising a fixed impedance, broad-band antenna; and a plurality of generally similar, multiplexed channels connected to said antenna, each channel including a broad-band, stepdown transformer having its high turns terminals connected to said antenna,

a series-resonant circuit connected across the low turns terminals of said transformer, the impedance of said circuit at resonance reflected thru its transformer being substantially matched to said fixed impedance of said antenna, and a signal amplifying means connected across a portion of said circuit.

4. A multiplex circuit comprising: broad-band transmission means; and a plurality of generally similar, multiplexed channels connected to said transmission means, each channel including a broad-band, step-down transformer having its high turns terminals connected to said transmission means, a series-resonant circuit connected across the low turns terminals of said transformer, the impedance of said circuit at resonance reflected thru its transformer being substantially matched to the impedance of said transmission means and being much higher off resonance, and a single amplifying means connected across a portion of said circuit.

5. A multiplex circuit comprising a fixed impedance, broad-band antenna; a plurality of generally similar broad-band, step-down transformers having their high turns terminals connected to said antenna; and an equal plurality of generally similar, series-resonant circuits connected, respectively, across the low turns terminals of said transformers, the impedance of each said circuit at resonance reflected thru its transformer being substantially matched to said fixed impedance of said antenna and being much higher off resonance.

6. A multiplex circuit comprising broad-band transmission means; a plurality of generally similar, broad-band, step-down transformers having their high turns terminals connected to said transmission means; and an equal plurality of generally similar, series-resonant circuits connected, respectively, across the low turns terminals of said transformers, the impedance of each said circuit at resonance reflected thru its transformer being substantially matched to the impedance of said transmission means and being much higher off resonance.

7. A multiplex circuit comprising a fixed impedance, broad-band antenna, a plurality of step-down broad-band transformers connected in parallel to said antenna, a plurality of tunable, series-resonant circuits connected, respectively, to the low turns terminals of said transformers, and a plurality of signal amplifying means connected, respectively, one across a portion of each said circuit.

8. A multiplex receiving circuit comprising a fixed impedance, broad-band antenna; a step-down, broad-band transformer having its high turns terminals connected to said antenna; a plurality of tunable, series-resonant circuits connected to the low turns terminals of said transformer, and a plurality of means for deriving signals from a portion of each said circuit.

9. A multiplex receiving circuit comprising broad-band transmission means; a step-down, broad-band transformer having its high turns terminals connected to said transmission means; a plurality of tunable, series-resonant circuits connected to the low turns terminals of said transformer, and a plurality of means for deriving signals from a portion of each said circuit.

10. A multiplex circuit comprising a fixed impedance, broad-band antenna; a step-down, broad-band transformer having its high turns terminals connected to said antenna; a plurality of series-resonant circuits connected to the low

turns terminals of said transformer, and a plurality of signal amplifying means connected, respectively, across a portion of each said circuit.

5 11. A multiplex circuit comprising broad-band transmission means; a step-down, broad-band transformer having its high turns terminals connected to said transmission means; a plurality of series-resonant circuits connected to the low turns terminals of said transformer, and a plurality of signal amplifying means connected, respectively, across a portion of each said circuit.

10 12. A multiplex circuit comprising a fixed impedance, broad-band antenna; a step-down, broad-band transformer having its high turns terminals connected to said antenna; and a plurality of series-resonant circuits connected to the low turns terminals of said transformer.

15 13. A multiplex circuit comprising broad-band transmission means; a step-down, broad-band transformer having its high turns terminals connected to said transmission means; and a plurality of series-resonant circuits connected to the low turns terminals of said transformer.

20 14. A multiplex receiving circuit comprising: a fixed impedance, broad-band antenna; step-down, broad-band transformer means having the high turns terminals thereof connected to said antenna; a plurality of generally similar multiplexed channels, each channel including a tunable, series-resonant circuit connected to the low turns terminals of said transformer means, the impedance of said circuit at resonance reflected thru said transformer means being substantially matched to said fixed impedance of said antenna and being much higher off resonance, and means for deriving a signal from a portion of said circuit.

25 15. A multiplex receiving circuit comprising: broad-band transmission means; step-down, broad-band transformer means having the high turns terminals thereof connected to said transmission means; a plurality of generally similar multiplexed channels, each channel including a tunable, series-resonant circuit connected to the low turns terminals of said transformer means, the impedance of said circuit at resonance reflected thru said transformer means being substantially matched to the impedance of said transmission means and being much higher off resonance, and means for deriving a signal from a portion of said circuit.

30 16. A multiplex circuit comprising: a fixed impedance, broad-band antenna; step-down, broad-band transformer means having the high turns terminals thereof connected to said antenna; a plurality of generally similar multiplexed channels, each channel including a series-resonant circuit connected to the low turns terminals of said transformer means, the impedance of said circuit at resonance reflected thru said transformer means being substantially matched to said fixed impedance of said antenna and being much higher off resonance, and signal amplifying means connected across a portion of said circuit.

35 17. A multiplex circuit comprising: broad-band transmission means; step-down, broad-band transformer means having the high turns terminals thereof connected to said transmission means; and a plurality of generally similar multiplexed channels, each channel including a series-resonant circuit connected to the low turns terminals of said transformer, the impedance of said circuit at resonance reflected thru said transformer means being substantially matched to the impedance of said transmission means and

11

being much higher off resonance, and signal amplifying means connected across a portion of said circuit.

18. A multiplex circuit comprising: a fixed impedance, broad-band antenna; step-down, broad-band transformer means having the high turns terminals thereof connected to said antenna; and a plurality of generally similar series-resonant circuits connected to the low turns terminals of said transformer means, the impedance of each said circuit at resonance reflected thru said transformer means being substantially matched to said fixed impedance of said antenna and being much higher off resonance.

19. A multiplex circuit comprising: broad-band transmission means; step-down, broad-band transformer means having the high turns terminals thereof connected to said transmission means; and a plurality of generally similar series-resonant circuits connected to the low turns ter- 20

12

minals of said transformer means, the impedance of each said circuit at resonance reflected thru said transformer means being substantially matched to the impedance of said transmission means and being much higher off resonance.
